COMBINED COLLAPSIBLE WALKER-STROLLER AND ADAPTER

Donald W. Gill, Amberly Village, Ohio, assignor to The Frank F. Taylor Company, Cincinnati, Ohio, a corporation of Ohio

Application June 24, 1957, Serial No. 46,707

Term of patent 14 years

(Cl. D14—14)

Figure 1 is a perspective view of a combined collapsible walker-stroller and adapter embodying my new design, in an upright position.

The dominant features of my design reside in the portions shown in full lines.

I claim:

The ornamental design for a combined collapsible walker-stroller and adapter, substantially as shown and described.
